E. R. BURTNELL

INTERNAL COMBUSTION ENGINE

Filed May 31, 1923

Inventor:—
Everett R. Burtnell.
By Martin Smith, atty.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed May 31, 1923. Serial No. 642,509.

My invention relates to internal combustion engines, the principal objects of my invention being to generally improve upon and simplify the construction of the present forms of internal combustion engines, and to provide an engine in which a power impulse is developed by a two stroke cycle and in which engine the valvular functioning is accomplished by means of reciprocating sleeves.

Further objects of my invention are, to provide a two stroke cycle combustion engine cylinder, in which the inlet and exhaust ports are opened, closed and sealed at the desired time, by one reciprocating sleeve actuated by direct connection with an eccentric on the crank shaft, and to provide in an internal combustion engine a two stroke cycle pumping cylinder for gaseous mixture precompression and pressure induction of the fresh charge into the combustion cylinder, in which the inlet port is opened, closed and sealed at the desired time by a single sleeve actuated by a direct connection with an eccentric on the crank shaft.

A further object of my invention is, to provide a two stroke cycle internal combustion engine, in which the gaseous mixture charge supply from the carburetor or vaporizing means to the pumping chamber, is supplied for the full time duration of the induction or suction stroke of the piston of the pumping chamber, providing thereby, increased volumetric efficiency, and reducing the fluctuation of the inlet column movement through the choke tube of the carburetor, and consequently making a two stroke cycle engine operation more silent, smooth and flexible.

A still further object of my invention is, to provide an internal combustion engine of few parts, functioning on the combustion cycle with constant compression, with silent and positive valve action, eliminating the need for a cam or eccentric shaft, timing gears and associated parts, and effecting a great saving in manufacturing and maintenance cost.

With the foregoing and other objects in view, my invention consists in certain novel features of construction and arrangements of parts hereinafter more fully described

and claimed, and illustrated in the accompanying drawings, in which—

Fig. 1 is a vertical section taken lengthwise through the center of an engine of my improved construction.

Fig. 2 is a horizontal section taken on the line 2—2 of Figure 1.

Referring by numerals to the accompanying drawings, which illustrate a practical embodiment of my invention, 10 designates the upper member of a crank case in the ends of which are formed suitable bearings 11 for a shaft 12 having a pair of cranks 13 and 14 that are oppositely disposed or arranged 180 degrees apart.

Formed on the shaft 12 adjacent to the crank 13, is an eccentric 15, and formed on said shaft adjacent to the crank 14 is an eccentric 16.

Surmounting the crank case 10 is a block that comprises a combustion cylinder 17 and a pumping or precompression cylinder 18, the axes thereof being substantially parallel.

The wall surrounding the combustion cylinder 17 is formed with a chamber 19 through which may be circulated a fluid cooling medium, such as water, and the greater part of the wall surrounding pumping cylinder 18 is provided with a chamber 20 through which may be circulated the hot burnt gases and products of combustion that are discharged from the combustion cylinder.

Formed through the upper portion of the wall of the pumping cylinder 18 is a gaseous fuel inlet port 21, and formed through the wall between the chambers within the two cylinders is a transfer port, or ports, such as 22, and through which the compressed gaseous fuel passes from the chamber within the pumping cylinder to the chamber within the combustion cylinder.

Formed through the upper portion of the wall of the combustion cylinder 17 and disposed substantially opposite to the transfer ports 22 is an exhaust port 23.

Arranged for reciprocatory movement within the piston sweep chamber 24 in the combustion cylinder is a sleeve 25, and formed in the upper portion thereof is a port 26 that is adapted to register with and

control the discharge of burnt products of combustion through exhaust port 23, and formed through the opposite portion of the wall of sleeve 25 and adapted to communicate with transfer ports 22, are ports 27.

Arranged for reciprocatory movement with sleeve 25 is a piston 28, and a connecting rod 29 connects the wrist pin of said piston with the crank 13.

10 Projecting laterally from the lower portion of the sleeve 25 is a trunnion 30 on which is journaled the upper end of a connecting rod 31, the lower portion thereof encircling eccentric 15.

15 In order to minimize wear upon the sleeve 25 and to eliminate angular strains that might be imparted thereto by the pull of the connecting rod 31, a cross-head 32 is mounted on the trunnion 30 between the 20 upper ends of the rod 31 and said sleeve, and the end of said cross-head is provided with plates 33 that bear on flat vertically disposed surfaces 34 that are formed within the lower portion of the cylinder block.

25 The chamber that is occupied by this cross-head and trunnion is closed by a readily removable plate 35.

A readily detachable head 36 closes the upper end of the combustion chamber, said 30 head having a substantially cylindrical depending portion 37 that extends downwardly within the piston sweep chamber 24, and the external diameter of such depending portion is such that it fits snugly within 35 the upper portion of sleeve 25.

This head and depending portion are formed with connected chambers 38 that communicate with the cooling fluid circulation chambers 19.

40 Formed in the lower portion of the depending member 37 of this head is a pocket 39, and leading therefrom downwardly and outwardly through the wall of the depending member 37, is a short duct 40 that communicates with a series of ports 41, and the latter being disposed directly opposite to the transfer ports 22.

When sleeve 25 is moved to a certain position, the ports 27 therein are adapted to 50 coincide with the ports 22 and 41, and consequently admit compressed gaseous fuel from the pumping cylinder to the pocket 39 and to the chamber 24 with which said pocket communicates.

55 Leading downwardly and laterally from the lower end of pocket 39 is a duct 42 that is inclined so that the gaseous fuel that discharges from the pocket 39 into piston sweep chamber 24 will be directed, as shown by 60 the arrows in Fig. 1, downwardly into that side of the piston chamber that is below the inlet ports and directly opposite from the exhaust port. Thus, when gaseous fuel is admitted to the piston sweep chamber, it 65 will sweep downwardly on the side opposite

from the exhaust port 23, thence across the top of piston 28, thence upwardly toward the exhaust port, thus very thoroughly sweeping through the entire piston sweep chamber, and driving out through the open 70 exhaust port, the burnt gases and products of combustion from the previously ignited fuel charge.

The lower edge of depending member 37 is cut away directly below exhaust port 23, 75 as designated by 43, thereby forming a short duct through which the products of combustion may pass during scavenging operations.

Fitted in the lower portion of the depending member 37 and bearing against the inner face of sleeve 25 is a packing ring 44.

Seated in the central portion of head 36 is an ignition device, preferably a spark plug 45, and the inner ends of the electrodes 85 thereof project into the upper portion of pocket 39.

Arranged for reciprocatory movement within the gaseous fuel compression chamber 46 in cylinder 18 is a sleeve 47 that controls gaseous fuel inlet port 21.

Projecting laterally from the lower portion of this sleeve is a trunnion 48, on which is journaled the upper end of a connecting rod 49, and the lower end of which latter 95 encircles eccentric 16.

Mounted on trunnion 48, is a cross-head 50, the construction and functions of which are identical with the cross-head that is mounted on trunnion 30.

Arranged for reciprocatory movement within sleeve 47 is a piston 51 that is provided with a recess 52 in its upper portion, and a connecting rod 53 connects the wrist pin of this piston with crank 14.

Inasmuch as the cranks 13 and 14 are oppositely disposed, the pistons 28 and 51 move simultaneously in opposite directions.

Eccentric 16 is set so that prior to the time crank 14 reaches low center, and piston 51 is at the lower end of its stroke, said eccentric and connections to sleeve 47 have drawn the latter downward to uncover port 21, thereby admitting from a suitable source of supply, preferably a carburetor, a charge 115 of gaseous fuel.

As the sleeve moves upward, the inlet port 21 is covered, thereby cutting off the further admission of gaseous fuel to the compression chamber 46, and on the subsequent upward stroke of piston 51, this charge of gaseous fuel will be highly compressed within said chamber 46, and at the same time the compressed charge will absorb a certain amount of heat from the heated products of combustion that are circulated through chamber 20.

While the gaseous fuel charge is under high compression, the sleeve 25 has been drawn downward by eccentric 15 and con-

nctions, so that ports 27 register with ports 22 and 41. As this registration of ports takes place, the compressed gaseous fuel charge rushes through transfer ports 22, 5 ports 27 and 41, thence through duct 40, pocket 39, and thence downwardly through duct 42, with the result that the burnt gases and products of combustion resulting from the previously ignited and expanded gaseous 10 fuel charge, will be forced out through port 26 that is in registration with the exhaust port 23.

As this exhaust or scavenging action is completed, eccentric 15 and connections will 15 move sleeve 25 upward so as to cut off the further inlet of compressed gaseous fuel into the pocket 39 and so as to cut off the further exhaust through port 23, with the result that the admitted charge of gaseous fuel will be 20 sealed within piston sweep chamber 24, and on the succeeding upward stroke of the piston 28, this gaseous fuel charge will be compressed within pocket 39.

As crank 13, passes high center, or im- 25 mediately thereafter, a spark is produced between the terminals of the electrodes of plug 45, thereby igniting the charge of compressed gaseous fuel within the pocket 39 and the expansion of combustion of the 30 compressed fuel charge will be directed against the head of piston 28 to move the same downward on its power stroke.

Before the piston 28 reaches the lower 35 end of its stroke sleeve 25 will have been moved so that port 27 registers with ports 22 and 41, and so that port 26 registers with exhaust port 23, thereby admitting a fresh charge of compressed gaseous fuel, and which charge in sweeping through cham- 40 ber 24 will force before it the burnt products of combustion, and the same will be discharged through ports 26 and 23.

Thus, it will be seen that I have pro- 45 vided a relatively simple and practical two stroke cycle internal combustion engine in which pocket valves, crank case compres- 50 sion cam shaft and timing gears are wholly eliminated, and which engine has the desirable feature of smooth, silent and flexible operation combined with simplicity of structure and low cost of manufacture.

Obviously, the construction of the various parts of my improved internal combustion engine may be varied in detail 55 without departing from the spirit of the invention, the scope of which is set forth in the appended claims.

I claim as my invention:

1. In a two stroke cycle internal com- 60 bustion engine, a combustion cylinder, a pumping cylinder, a sleeve arranged for reciprocation within said combustion cylinder, a sleeve arranged for reciprocation within the pumping cylinder, a piston arranged 65 for reciprocation within the sleeve of the

combustion cylinder, a piston arranged for reciprocation within the sleeve of the pumping cylinder, a crank shaft, a connection between the piston of the combustion cylinder and one of the cranks of said 70 crank shaft, a connection between the piston of the pumping cylinder and a second crank of said crank shaft, an eccentric on the crank shaft, and a connection between the sleeve of the combustion cylinder and 75 said eccentric, a second eccentric on the crank shaft, a connection between the sleeve of the pumping cylinder and said second eccentric, there being a gaseous fuel admission port formed near the top of the 80 pumping cylinder, there being a duct leading from the compression clearance part of the pumping cylinder to the upper part of the combustion cylinder, there being a port in the sleeve of the combustion cylinder for 85 registration with said duct, there being an exhaust port formed in the wall of the combustion chamber at a point substantially opposite to said duct, a head projecting 90 into the inner or head end of the combustion chamber, which head is provided with an ignition pocket, ports formed in said head for establishing communication between the port in the sleeve surrounding the piston in the combustion chamber with 95 said ignition pocket and a port leading from the lower portion of said ignition pocket to the bottom of said head.

2. A two stroke cycle internal combustion engine having a combustion cylinder and a 100 pumping cylinder, said pumping cylinder having a gaseous fuel inlet port, the combustion cylinder having an exhaust port, there being transfer ports formed between the chamber within the pumping cylinder 105 and the chamber within the combustion cylinder, a crank shaft having a pair of cranks, a piston within the combustion chamber, which piston is connected to one of the cranks of the crank shaft, a piston 110 within the pumping cylinder, which piston is connected to the other crank of said crank shaft, a sleeve within the pumping cylinder and enclosing the piston therein, which sleeve controls the gaseous fuel in- 115 let port, an eccentric on the crank shaft, a connection from said eccentric to said sleeve, a sleeve within the combustion chamber for controlling the transfer ports and the exhaust port, said sleeve enclosing the 120 piston within said combustion chamber, a second eccentric on the crank shaft, a connection from said eccentric to said last mentioned sleeve, a head projecting downwardly into said combustion chamber, which 125 head is provided with a combined compres- sion and ignition pocket that receives the gaseous fuel that is admitted through the transfer ports and a port leading from the lower portion of said ignition pocket down- 130

wardly through the bottom of said head and communicating with the piston clearance space within said combustion chamber.

3. In an internal combustion engine, the combination with a combustion cylinder having an exhaust port that leads from the piston sweep chamber within said sleeve, a head for said cylinder, said head having a combined gaseous fuel compression and 10 ignition pocket, there being a duct leading downwardly from said pocket in an inclined direction toward the side of the piston sweep chamber opposite to the side in which the exhaust port is formed, there being 15 a gaseous fuel inlet port formed in the

cylinder and adapted to communicate with the pocket in the cylinder head, a sleeve arranged for reciprocatory movement within said cylinder and provided with ports that are adapted to register with said inlet port and exhaust port, and a gaseous fuel pumping cylinder arranged immediately adjacent to said combustion cylinder for compressing gaseous fuel and forcing the same under pressure through said inlet 20 port.

In testimony whereof I have signed my name to this specification.

EVERETT R. BURTNELL.
